UNITED STATES PATENT OFFICE

ARTHUR R. BLOOM, OF MINNEAPOLIS, MINNESOTA

SIGN DEVICE

Application filed April 27, 1927. Serial No. 186,946.

This invention relates to a sign or display device and particularly to such a device constructed and arranged alternately to display different pictures or signs. It is a well known fact that the attention of the public is much more easily drawn to a picture which moves or changes than to a picture which is in stationary form or condition. It is desirable, therefore, to have an advertising device which changes or displays different pictures or inscriptions. It is also desirable, in an advertising device arranged for use by some particular institution, to have permanent inscriptions thereon particularly applicable to said institution.

It is also desirable, to have an advertising device of simple and inexpensive construction and one which can be inexpensively operated.

It is an object of this invention, therefore, to provide a simple and efficient display or advertising device, constructed and arranged alternately to display different pictures or inscriptions, and preferably also display the name of the advertiser.

It is a further object of the invention to provide an advertising or display device constructed and arranged to display different pictures or inscriptions with illuminating means.

It is another object of the invention to provide a sign or display device arranged alternately to display different pictures or inscriptions, the same being so constructed as when illuminated at certain time, to give the picture an effect of relief.

It is still another object of the invention to provide a sign or display device having a simple and efficient cabinet arranged effectively to display the pictures or inscriptions, and also constructed and arranged to readily permit insertion of different pictures or inscriptions.

These and other objects and advantages of the invention will be fully set forth in the following description made in connection with the accompanying drawings, in which like reference characters refer to similar parts throughout the several views and in which:—

Fig. 1 is a view in front elevation of the cabinet used;

Fig. 2 is a vertical section taken on line 2—2 of Fig. 1, as indicated by the arrows;

Fig. 3 is a horizontal section taken on line 3—3 of Fig. 1 as indicated by the arrows;

Fig. 4 is a view in front elevation of one side of a sheet used with the device;

Fig. 5 is a partial view of the other side of the sheet shown in Fig. 1;

Fig. 6 is a view of one side of the second sheet used; and

Fig. 7 is a partial section similar to Fig. 3 shown on an enlarged scale.

Referring to the drawings, particularly Figs. 1 to 3, a cabinet is shown comprising a bottom member 10 having an upper flat portion with front and rear flanges 10^a and 10^b respectively extending substantially at right angles therefrom and forming supporting means therefor.

The member 10 also has an upwardly projecting front flange 10^c extending above its top flat portion. The said cabinet has a rear wall 11 which has forwardly inclined portions 11^a at each side and forwardly extending portions 11^b extending

therefrom and substantially at right angles to its main rear portion. Guide channels 11^c are provided, having their channels fac-

ing inwardly and towards each other be-

tween the front part of the portions 11^b and while these channel members may be vari-

ously formed and constructed, in the embodiment of the invention illustrated they are shown as formed by folding and bending the

member from which parts 11^a and 11^b are formed.

While the members 10 and 11 may be formed of various materials, they are illus-

trated as formed from some sheet ma-

terial such as metal. Disposed in the guide

members 11^a and slidably and removably

engaging the same are the guide members 12

illustrated as formed from a folded piece

of sheet material or metal having rectangu-

lar channels at their inner sides facing each

other. A pair of transparent plates 13 are

shown as disposed in the guide channels of

members 12 and said plates have disposed

therebetween a plurality of translucent sheets

14 to be later described. It may be stated

60

65

70

75

80

85

90

95

100

that the member 11 with its portions 11^a and 11^b extends downwardly at the rear and sides of the member 10, as shown in Fig. 2. Disposed at each side of the member 11 and forwardly thereof, is an auxiliary casing 15 illustrated as being rectangular in cross section and as having a rearwardly extending flange 15^a extending along the outer side of the portion 11^b. The rod 16 extends across the casing and through each of the portions 11^b and 15^a, having its ends threaded and equipped with wing nuts 17, thus holding casings 15 against the member 11. The casings 15 have U-shaped plates 18 secured therein adjacent their lower ends forming the bottoms therefor, and as shown in Fig. 3, the sides of the casings 15 which are directed inwardly or toward the plates 18, have openings therein and flanges 15^b extend from these sides inwardly and toward the plates 18. The front sides of the casings 15 also have openings 15^c cut therein and said casings have small angle members 19 secured at their inner sides, forming, with the portions at the sides of the openings 15^c channel shaped guides. Transparent plates 20 are disposed in said guides, thus extending across the openings 15^c, which plates are adapted to have disposed therebetween one or more translucent sheets 21 to be later described. The casings 15 have removable tops 22 which when removed, give access to the plates 21 which are thus slidably removable from their guide members. A top or lid 23 is provided for the cabinet, having the greater portion of its surface sloping downwardly toward the rear as shown in Fig. 2, but having horizontal portions 23^a at each side, said lid having a downwardly extending flange 23^b at its rear and ends overlapping the top of the member 11. The lid at its front between the flat portions 23^a has inwardly extending side flanges 23^c which are disposed in planes slightly in the rear of the front edge of the said top, said front edge having a downwardly extending flange 23^d which overlaps the flanges 15^b being disposed between the inner sides of the casings 15. The front of said top has a flange 23^e extending upwardly and a pair of transparent plates 24 are disposed in the rear of the flanges 23^c and in front of the flange 23^d and in front of the small vertically extending flange 23^f at the upper portion of the top 23. The flange 23^f normally extends slightly rearward and has a U-shaped or channel shaped portion 26 of resilient sheet material which extends over the front edge of the plates 24. The bottom member 10 carries a pair of lamp sockets 27 adapted to receive the electric lamp bulbs 28 which are thus disposed between the member 11 and the plates 13, the inner surface of member 11 preferably being formed with high reflecting capacity. The members 18 in the casings 15 also have standards secured there-

to carrying lamp sockets 29 adapted to receive the lamp bulbs 30 and the inner sides of casings 15, and the inner side of the flanges 15^b are also formed as reflecting surfaces. Electrical conductors 31 are shown as extending into a box or casing 32 containing a flashing mechanism secured to the under side of the member 10, which conductors extend to lamp sockets 27 and other conductors 33 extend from casing 32 to the lamp sockets 29. The flashing mechanism 32 will alternately illuminate and extinguish the lamps 28 and 30. Such flashing devices are now well known and need not be further shown or described.

The cabinet described is adapted to receive advertising material for some institution such as a bank and the sheet 25 between the plates 24 may have the name of the bank thereon as indicated in Fig. 1. The sheets 21 between the plates 20 which sheets will be translucent, may have thereon words such as shown in Fig. 1, which indicate the characteristics or qualities of the institution. A colored translucent sheet may be placed in the rear of or in the front of the sheet carrying the desired words such as "Strength" and "Service" shown in Fig. 1.

The sheets 14 disposed between the plates 13 will carry various pictures or inscriptions related to the business or work of the institution using the advertising device. One set of sheets which may be used between plates 13 is shown in Figs. 4 to 6. The side of the sheets adjacent the front plate 13 is shown in Fig. 4. This picture represents the front of a theatre including the stage, the boxes at each side thereof and the orchestra pit. It will be seen that on the center of the curtain a white space is shown with the inscription "Make your next act a wise one", with the figure of the owl therein. Lamp bulbs 34 are shown surrounding the stage and lamp bulbs 35 are shown on the boxes as well as lamp bulbs 39 representing the footlights. The picture will be put up in colors and certain colors are indicated in Fig. 4, the curtain 36 being indicated as blue, as are also the draperies 37 for the boxes. The decorations 38 at the sides and top of the stage are indicated as red. Other portions of the picture will also be colored.

The sheet shown in Fig. 4, which as stated, is the front sheet, has on its reverse side the picture shown in Fig. 5. This picture is arranged to coincide with the picture shown in Fig. 4 and also has inscriptions thereon, which are reversed so that they will show through the sheet in correct position. One of these inscriptions in the large letters is "Savings account", while above the same in small letters occur the words "Come in and start a". It will be seen that a large part of the sheet shown in Fig. 5 is in black as indicated at 40 which part is opaque, which black portion aligns with the box portions of the picture on

the obverse side of the sheet. The sheet also has a portion 41 indicated as red and this portion alines with the decorative strip around the stage on the obverse picture including the members 38 and the parts carrying the lights 34. The picture also has vacant spaces or white spaces 42 alined with the curtain 36 on the obverse side and with the black portions immediately inside of said curtain. 5 The portion 43 indicated as green alines with the white space at the other side of the picture and it will be seen that there are also wings 44 adapted to fit at each side of the picture of the owl at the obverse side in front of which 10 certain pieces of money are shown, the central part of the owl being shown in white. The picture also contains white spaces 45 which aline with the sheets of music 45^a on the music racks of the orchestra shown in Fig. 4. 15 There are also small round white spaces 46 which aline in the picture on the other side with the lamps 34 about the stage and also the lamps 35 about the boxes. There is also a 20 white strip or portion 47 which alines with the space on the obverse side extending between the lines between which the lamps 39 are shown.

Another sheet 14^a is used in the rear of the front sheet 14 and this sheet has on its 30 front side a picture similar to the pictures shown in Fig. 4 including the words "Savings account". Said sheet also has on its reverse side a picture similar to the picture shown in Fig. 5. The rear sheet 14^a, however, has certain portions thereof cut out or 35 cut away. These portions, as shown in Fig. 6, comprise the lower portions or balcony portion of the boxes 48. Other cut out portions include the owl at the center including 40 the wings thereof and the pieces of money adjacent thereto as shown at 49 and the rectangular portion 50 which alines with the words shown in reverse in Fig. 4, "Come in and start a". There is also a cut out portion 51 alining 45 with the portion in Fig. 4, showing the floor of the stage in front of the curtain including the space in which the footlights 39 are disposed and there are cut out portions 52 coinciding with the white spaces 45 shown in 50 Fig. 5 and the pieces of music on the music racks of the musicians shown in Fig. 4. There is also a cut out space 54 which alines with the rectangular spaces shown in Fig. 4, bearing the letter A indicating the particular act. 55 The sheet 14^a shown in Fig. 6 also has small cut out portions 53 which aline with the lights 34 around the sides of the stage as shown in Fig. 4.

The ink used for the different colors on 60 sheet 14 is of different intensities for said colors respectively.

In operation the sheets 14 and 14^a are placed between the plates 13 and the picture shown in Fig. 4 is seen through the front plate 65 13. The lamps 28 are then at first extinguished

and the lamps 30 in casings 15 are lighted. When the lamps 30 are lighted, the words on the sheets 21 between the plates 20 at the front of the casings 15 are illuminated, these words being shown as "Strength" and "Service". The words at the top of the cabinet will also be visible, although not illuminated. The lamps 28 and 30 are periodically alternately lighted and extinguished. The light from the lamps 30 is directed against the front of the picture shown in Fig. 4, so that the picture is illuminated by reflected light and it appears merely as shown in Fig. 4. When the lamps 30 are extinguished and the lamps 28 lighted, the picture shown in Fig. 5 which is on the reverse side of the front sheet 14 is also seen and blends with the picture shown in Fig. 4. A composite effect is thus obtained of the pictures on the front and rear of sheet 14. The wings 44 appear on the owl as well as the pieces of money. A green tinge is given to the central part of the picture and both the inscriptions shown in Fig. 4 and that shown in Fig. 5 are visible. Furthermore, the light from the lamps 28 shines through the openings 48 to 54 and the portions of the pictures on the front sheet in alinement with these openings are accentuated. The owl and the money adjacent the same, the words "Come in and start a", the front of the stage, the rectangles having the letters A therein and the lamps about the stage and the boxes, as well as the sheets of music on the racks of the musicians are thus illuminated more highly than the other parts of the picture. This accentuated illumination is also assisted by the white portions on the rear of the front sheet 14 as shown in Fig. 5. The accentuated illumination is given a differential effect by the different intensities of the ink used in making the different colors. This differential illumination is effected on different parts of the picture, as the curtains, the green portion 43 and the different parts of the owl figure. This accentuated illumination causes the parts so illuminated to stand out and give the effect of being in relief. The change caused in the picture is quite striking and the added information given by the inscriptions on the rear of the front sheet 14 constitute a very striking advertisement. If desired, colored sheets 21 may be inserted between the plates 20 so that when the lamps 30 are illuminated, there will be a colored border about the words on the sheet 21.

From the above description it is seen that applicant has provided a very simple and highly effective advertising device. The same is merely connected to a source of electric current such as an ordinary socket or plug and the device then functions automatically to display the sign in its two conditions. The change is made at periods of three seconds or more and an attractive sign is thus pro-

vided. In practice a series of pictures are used which are changed at intervals so that fresh subject matter is frequently displayed. The illumination when the device is operated 5 as described, gives the effect of an animated picture, part of which is brought out in relief and the information which it is desired to emphasize or to impress upon the observers is very effectively exhibited. The device has 10 been demonstrated in actual practice and found to be very successful and efficient.

It will, of course, be understood that various changes may be made in the form, details, arrangement and proportions of the 15 parts, without departing from the scope of applicant's invention, which, generally stated, consists in a device capable of carrying out the objects above set forth, in the novel parts and combinations of parts disclosed 20 and defined in the appended claims.

What is claimed is:—

1. A sign display device having in combination, a translucent sheet having a picture on its front side adapted to be illuminated and viewed by reflected light, said sheet having a picture on its opposite side aligned with said picture adapted to be viewed compositely therewith by light passing through said sheet, means separate from 25 and in the rear of said sheet of similar outline to and covering certain portions of said first mentioned picture but exposing others, a light source forward of said sheet and a light source in the rear of said sheet, 30 said sources of light being adapted to be alternately operated whereby when said last mentioned light source is operated, portions 35 of said pictures are accentuated and a relief effect produced.

2. A sign display device having in combination, a translucent sheet having a picture on its front side adapted to be illuminated and viewed by reflected light, said sheet having a picture on its opposite side aligned with 40 said picture adapted to be viewed compositely therewith by light passing through said sheet, a second sheet in the rear of said first mentioned sheet having openings therein coinciding with certain portions of said pictures, a light source forward of said sheets and a light source in the rear of said sheets, 45 said light sources adapted to be alternately operated whereby said first picture will be seen when said first light source is operated 50 and a composite picture will be seen when said second light source is operated.

3. A sign display device having in combination, a translucent sheet having a picture on its front side adapted to be illuminated and viewed by reflected light, said sheet having a picture on its opposite side aligned with said picture adapted to be viewed compositely therewith by light passing through said sheet, a second sheet in the 55 rear of said sheet having similar pictures

aligned with said pictures openings therein coinciding with certain definite portions of said pictures, a light source forward of said sheet and a light source in the rear of said sheet being adapted to be alternately operated whereby when said first light source is operated, said first mentioned picture will be seen and when said second mentioned light source is operated, both pictures will be seen and the parts aligned with said openings will have additional illumination so that a relief effect is produced.

4. A sign display device having in combination, a translucent sheet having a picture on its front side adapted to be illuminated and viewed by reflected light, said sheet having a picture on its opposite side aligned with said picture adapted to be viewed compositely therewith by light passing through said sheet, a second sheet in the rear of said sheet having pictures on its front and rear sides similar to those on said first mentioned sheet and coinciding therewith, said second sheet having certain portions of said pictures cut out, a light source disposed forward of said sheet and a light source disposed in the rear of said sheet.

5. A sign device having in combination, a casing having rear and side walls, guides at the front of said side walls, a pair of transparent plates removably disposed in said guides and forming the front of said casing, a translucent sheet having co-operating pictures on its opposite sides, a sheet in the rear of said translucent sheet having spaced cut-out portions alining with parts of said pictures, a light source between said rear wall and plates, said casing having chambers at each side of and forward of said plates having openings at their sides which are directed toward each other and toward said plates, and a light source in said chambers whereby a light will shine therefrom onto the front of said plates and sheets.

6. A sign device having in combination, a casing having rear and side walls, guides at the front of said side walls, a pair of transparent plates removably disposed in said guides and forming the front of said casing, a translucent sheet having co-operating pictures on its opposite sides, a sheet in the rear of said sheet having cut-out portions alined with parts of the pictures on said sheets, a light source between said rear wall and plates, said casing having chambers at each side of and forward of said plates having openings at their sides which are directed toward each other and toward said plate, a light source in said chambers whereby a light will shine therefrom onto the front of said plates and sheets.

7. A sign device having in combination, a casing having rear and side walls, a transparent plate forming the front of said casing, means for holding one or more translucent

70

75

5 sheets in the rear of said plate, a light source between said plate and said rear wall, chambers at the side of and forward of said transparent plate, guides at the front sides of said chambers, a pair of transparent plates disposed in said guides and vertically removable therefrom, an inscription bearing translucent sheet between said plates a light source in each of said chambers illuminating said last 10 mentioned translucent sheets, said chambers having openings through which light is directed by said last mentioned light source against said transparent plate.

15 8. A sign display device having in combination, a translucent sheet having a picture on its front side adapted to be illuminated by reflected light, said sheet having areas on its opposite side of different densities and alined with portions of the picture on the 20 front side, whereby when light shines through said sheet, different portions thereof will be illuminated with different intensities, a light source forward of said sheet and a light source in the rear of said sheet, said sources of 25 light being adapted alternately to be operated whereby portions of the pictures having ink of lesser density will be accentuated in illumination and an impression of relief produced.

30 9. A sign display device having in combination, a translucent sheet having a picture on its front side adapted to be illuminated and viewed by reflected light, said picture being printed with ink of different densities 35 and comprising some white or unprinted portions, said sheet having on its opposite side areas printed with ink of different densities, said areas alining respectively with portions of said picture on the front side of 40 said sheet, a light source forward of said sheet and a light source in the rear of said sheet, said sources of light being adapted to be alternately operated whereby when said last mentioned source is operated, portions 45 of said pictures are illuminated with greater intensity than others and a relief effect produced.

50 10. The structure set forth in claim 9 and a second translucent sheet in the rear of said first sheet similar to said first sheet but having portions cut therefrom alining with certain portions of the picture on the front of said first sheet.

55 11. A sign display device having in combination, a translucent sheet having a picture on its front face adapted to be illuminated and viewed by reflected light, said sheet having a similar picture on its opposite side alined with said picture but having parts of 60 the picture printed in different colors, a similar sheet in the rear of said first mentioned sheet in close proximity thereto having similar pictures thereon but having parts thereof cut away, a light source forward of said sheets, and a light source in the rear of said

65 sheets, said light sources being adapted to be alternately operated, whereby when said last mentioned light source is operated, portions of said picture are accentuated and a relief effect produced.

70 12. A sign device having in combination, a translucent sheet having a picture on its front side adapted to be illuminated and viewed by reflected light, said picture being in different colors and comprising some portions white or unprinted, said sheet having areas on its opposite side of different colors adapted to aline with said portions of said picture on said front side which are white or unprinted, and a second translucent sheet in the rear of said first mentioned sheet similar to said first mentioned sheet but having certain portions cut therefrom adapted to aline with different portions of the picture on said first mentioned sheet.

75 80 In testimony whereof I affix my signature.
ARTHUR R. BLOOM.
